HEAD APPAREL

Evelyn McCaffrey, Jamaica, N. Y.

Application January 23, 1946, Serial No. 642,861

5 Claims. (Cl. 2—174)

1

My invention relates to improvements in head apparel.

Head apparel, including bathing caps and hats of variant types, usually of one piece construction, as heretofore proposed and in present use, are positioned on the head by movement downwardly relative to the hair of the head of the wearer. As a result, the free strands of the wearer's hair adjacent the perimetric hairline remain or are displaced downwardly when such prior or present head apparel is in final position on the wearer's head. To dispose such projecting hair strands within such head apparel, it is necessary to tuck them under, an operation causing inconvenience and frequently but partially successful, particularly in regard to such free strands at the back of the head.

Contrary to such prior and present head apparel, embodiments of my invention are formed of two members, one member of which is usually in the form of a band, and desirably of resilient nature, and in the operation of placing my head apparel upon the head such band member is first brought completely over the head, and then moved upwardly, in which upward movement the free strands of the hair of the head of the wearer extending beyond the perimetric hairline are automatically moved inwardly of such hairline; upon final positioning of such band member, namely locating the lower edge of the band member at or adjacent such hairline, all strands of the hair of the wearer are brought and secured within the relatively wide expanse of the band member. The central portion of the hair of the head of the wearer may be covered by a supplemental crown member, serving as a closure member to cover the central portion of the hair of the head of the wearer. Such closure member has a shape conforming to the style of coiffure of the wearer and accordingly is of the variant formation, ranging from a simple segment of a sphere to segments of geometrical configuration and having depths corresponding to the height of the coiffure.

Such closure member may be permanently partially attached to the inner periphery of the band member or may be a separate part and attached to the band member by suitable detachable fastening means of such character as may be preferred.

Further features and objects of the invention will be more fully understood from the following detailed description and the accompanying drawings, in which:

Fig. 1 is an illustrative perspective side view of a preferred embodiment of the invention, comprising a partially attached supplemental member, showing an initial stage of the procedure in applying my head apparel to the head of a wearer.

2

Fig. 2 is an illustrative perspective view similar to Fig. 1, and showing a later and intermediate stage of the procedure.

Fig. 3 is an illustrative perspective rear view of the embodiment of Figs. 1 and 2, showing the band member applied to a wearer's head and the partially attached supplemental crown member in open position.

Fig. 4 is an illustrative perspective side view of the embodiment of Figs. 1, 2 and 3, showing the head apparel fully applied to the head of the wearer, the partially attached supplemental member being fully attached to the band member.

Fig. 5 is an illustrative perspective rear view of head apparel as it appears in Fig. 4.

Fig. 6 is an illustrative perspective side view of another embodiment of the invention, comprising a partially attached supplemental member, shown in its open position.

Fig. 7 is an illustrative perspective view of the embodiment of Fig. 6, and showing the supplemental member in its closed position.

Fig. 8 is an illustrative perspective side view of another embodiment of the invention, comprising a wholly detachable supplemental member, indicating such supplemental member placed above the head of the wearer, preliminary to being attached to the band member.

Fig. 9 is an illustrative perspective side view of the embodiment of Fig. 8, showing the supplemental member fully attached to the band member.

Referring to the embodiment illustrated in Figs. 1 through 5, 10 designates generally the head apparel. This embodiment comprises the band member which is designated 11 and the supplemental crown member 12. In this embodiment the supplemental member 12 is partially attached to the band member 11 along the line of connection indicated by the dash line 13 in Figs. 1 and 4, which extends around the front of the head apparel from side to side thereof as indicated by the terminal points 14, 14, Fig. 3. Such supplemental member 12 is arranged to be fully attached to the band member 11, as by suitable detachable attachment elements, such as two-part snap fasteners, two such two-part snap fasteners being indicated in Figs. 1 through 5. The indicated two-part snap fastener elements are respectively designated 15, 15a.

The above described embodiment is applied to the wearer's head indicated generally by 16 as by initially placing the rear portion of the band member 11 at or about the rear of the head, as illustrated in Fig. 1, and moving the front portion of the band member over the head and the entirety of the head apparel about the neck, and thereafter moving upwardly the head apparel, both in front and at the rear, relative to the hair of the head of the wearer, until the

head apparel is positioned about the head of the wearer, as desired, as is indicated in Fig. 3. In this position the band member 11 hugs the head and the ears of the wearer. In such procedure the opening (indicated at 17 in Figs. 1 and 3) of the head apparel enables the head of the wearer to protrude therethrough. After such procedure, as shown in Fig. 4, the supplemental member 12 is fully attached to the band member 11 by closing the snap fasteners.

Preferably, the back lower margin 12a of the supplemental member 12 overlaps the upper outer margin of the band member about the opening 17, whereby water or other foreign material is shed over the jointure between the supplemental member and the band member.

The embodiment illustrated in Figs. 6 and 7 is generally similar to that of the preceding embodiment with respect to the construction of the band member, and likewise is designated 11. The supplemental member, designated 18, of the embodiment shown in Figs. 6 and 7, differs with respect to the supplemental member 12 of the above described embodiment in respect to its contour to accommodate a higher type of coiffure of the wearer as indicated at 19 as compared with the coiffure of the wearer as indicated in Figs. 1, 2 and 3. The supplemental member 18 of the embodiments shown in Figs. 6 and 7, also, is provided with a relatively wider rim portion 18a as compared with the rim portion 11a of the supplemental member 11 of the preceding embodiment. Both embodiments include the completion of the closing of the supplemental member with respect to the band member, as by the employment of two-part snap fasteners 15, 15a, or equivalent disconnectible connecting means.

The embodiment illustrated in Figs. 8 and 9 comprises a supplemental member, designated 20, which is wholly separable with respect to the band member 11. Pursuant to this embodiment, the band member may be of one width, such as in the form of a uniform band. The supplemental member may be attached to the band member, after the band member has been positioned upon the head of the wearer as by the procedure illustrated in Figs. 1, 2 and 3, whereafter the supplemental member 20 is affixed to the band member as by means of snap fasteners indicated at 15, 15a, four being indicated in Figs. 8 and 9, or equivalent detachable connecting means. Fig. 9 illustrates this embodiment fully applied to the wearer's head.

As indicated hereinabove, the material of the band member in the variant embodiments of the invention is of a yieldable nature, and for the types employed as bathing hats or caps, sportswear or the like is of resilient nature. The supplemental member in the types shown in Figs. 1 through 5, and Figs. 6 and 7 may be of the same material as and fashioned in its making continuous with the band member, or of different material or nature and attached to the band member at the margin of the partial attachment of the supplemental member to the band member. In the types of the embodiment illustrated in Figs. 8 and 9 the material of the band member is of yieldable, and preferably of resilient nature, as in the embodiments of Figs. 1 through 5 and Figs. 6 and 7, and the material of the supplemental member may be selected as may be preferred by the user. In any event the supplemental crown member 12 overlaps the upper outer margin of the resilient band member and extends downwardly over a part only of the band member.

The degree of flexibility or yieldability or resiliency of the material of the band member and the commensurate peripheral dimension of the band member may be selected to yield proper fit of the head apparel for a range of head sizes, consistent with comfort to the wearer.

I claim:

1. An apparel for human head wear comprising in combination a member of relatively wide resilient band formation freely stretchable during placement and adapted to snugly hug and encompass the outer perimetric line of the hair of the wearer; and a supplemental crown member detachably attached to the upper outer margin of said band member in overlapping relationship therewith.

2. Headgear comprising a relatively wide resilient band member freely stretchable during placement and adapted to hug the head of a wearer at and adjacent the hair line; a supplemental crown member; and fastening means for securing said crown member to the upper outer margin of said band member in overlapping relationship therewith.

3. Headgear comprising a relatively wide resilient band member freely stretchable during placement and adapted to hug the head of a wearer at and adjacent the hair line; a supplemental crown member partially secured to said band member, the free portion of said crown member being arranged to be pulled down over said resilient band member, overlapping the same, when the headgear is being worn; and fastening means for securing the said free portion of said crown member to said resilient band member in its said overlapping relationship therewith.

4. An apparel for human head wear, comprising in combination a member of relatively wide resilient band formation freely stretchable during placement and adapted to snugly hug and encompass the outer perimetric line of the hair of the wearer; a supplemental crown member permanently attached to the upper outer margin of said band member at the front thereof; and fastening means for attaching the rear portion of said supplemental crown member to said band member.

5. Headgear comprising a relatively wide resilient band member freely stretchable during placement and adapted to hug the head and ears of a wearer at and adjacent the hair line; and a supplemental crown member partially secured to said band member along the upper outer margin thereof, the free portion of said crown member being arranged to be pulled down over the upper outer margin of said resilient band member, overlapping the same; and a part only of said band member, when the headgear is being worn.

EVELYN McCAFFREY.
